UNITED STATES PATENT OFFICE.

EDWARD W. MITCHELL, OF CLEVELAND, OHIO.

CLOTHES DRIER.

Application filed February 9, 1923. Serial No. 617,992.

The objects of the invention are to provide an improvement in laundry driers for apartments, hotels or dwellings in which the air is caused to circulate continually about the fabrics in such a manner as to absorb the moisture therefrom and dry them completely.

The invention comprises a chamber open at the bottom and enclosed in an outer casing from which it is spaced on top and bottom and sides to permit free circulation of air thereabout.

Within this chamber are secured slidingly movable racks upon which the laundry may be hung, and a blower of any suitable design is positioned in the upper part of the chamber to cause a continual downward circulation of air therethrough, which after passing upward about the sides of the chamber within the casing is returned through the chamber.

The invention is hereinafter described, illustrated in the accompanying drawings and specifically pointed out in the claims.

In the accompanying drawings, Fig. 1 is a vertical longitudinal section of the device, Fig. 2 is a front elevation thereof.

In these views, 1 is a chamber open at 2 at the bottom and otherwise closed on all sides at the upper end of this chamber are shown horizontal metal rods 3 3 which project beyond the front wall thereof, and are connected together at their outer ends by means of a cross bar 4.

Upon these rods the racks 5 5 slide freely and are composed of longitudinal bars 6 6 vertically spaced apart, and vertical connecting and supporting members, 5 and 8 at their rear and front ends respectively 40 which are suspended from the rods 3, 3. These racks can be drawn out of the chamber, through the vertical openings 9 9 in the front wall. The front supporting member 8 comprises an elongated plate which 45 closes the corresponding opening 9 when the rack is pushed back with the chamber.

Handles 10, 10 upon the outer faces of these plates are employed for pulling them out and returning them to their places in 50 the chamber.

A casing 14 encloses this chamber and is spaced therefrom on the sides and rear. Legs 15, 15 raise the chamber from the floor. The front walls of the chamber and 55 casing may be the same and the openings 9, 9 will pass therethrough.

A blower or fan 11 is mounted upon the top of the chamber and propels a current of air continually through a central opening 12 therein.

The air thus propelled will pass downward through the laundry in the chamber, and will extract the moisture therefrom.

The air will then pass out of the open bottom of the chamber and will then pass 65 upward around the sides of the casing and will be returned by the fan into the chamber.

The fan may be operated by a motor 13 mounted upon the upper wall of the casing 70 and is removable therewith.

Having described the invention what I claim as new and desire to secure by Letters Patent is:—

1. In a device for the purpose described, 75 in combination, a chamber, and an enclosing casing spaced therefrom, vertical racks slidingly movable in said chamber, the vertical front wall of said chamber being provided with openings through which said 80 racks are drawn, said racks being provided with means for closing said openings, said chamber being open at the bottom and raised above the floor, and a blower mounted upon said casing over said chamber said chamber 85 being provided with an opening through which said air is propelled downwardly into said chamber by said blower.

2. In a device for drying clothes, in combination, a casing, a chamber elevated 90 therein and open at the bottom, said casing and chamber having a common front wall and spaced apart at the top, bottom, and sides and rear, said front wall being provided with vertical spaced openings, racks 65 slidable into and out of said chamber through said vertical openings, said racks being provided with front members adapted to close said openings when said racks are withdrawn into said chamber, said chamber being provided with an opening in its upper wall a fan for propelling the air downwardly through said opening, from the spaces about the sides of said chamber, and through said chamber, out of its bottom 100 into said side spaces.

In testimony whereof, I hereunto set my hand this 15th day of December 1920.

EDWARD W. MITCHELL.
